(57) **CLAIM**

The ornamental design for a cosmetic container, as shown and described.

DESCRIPTION

FIG. 1 is a perspective view of a cosmetic container of the present design;

FIG. 2 is a bottom plan view of the cosmetic container of FIG. 1;

FIG. 3 is a top plan view of the cosmetic container of FIG. 1;

FIG. 4 is a front elevational view of the cosmetic container of FIG. 1;

FIG. 5 is a rear elevational view of the cosmetic container of FIG. 1;

FIG. 6 is a left side elevational view of the cosmetic container of FIG. 1; and,

FIG. 7 is a right side elevational view of the cosmetic container of FIG. 1.

The broken lines shown in the drawings are for environmental purposes only and form no part of the claimed design.
